UNITED STATES PATENT OFFICE

THEODORE HILL, OF BALTIMORE, MARYLAND

MOTION PICTURE MACHINE

Application filed February 29, 1928. Serial No. 257,921.

This invention relates to improvements in moving picture machines.

Heretofore, in order to save unnecessary delay in the projection of moving pictures, it was necessary to provide two separate machines in which were mounted the consecutive reels. When the reel in one machine was completely unwound the other machine, in which was mounted the following reel, was set in operation. Such a method presented two outstanding disadvantages. Due to the duplication of equipment the installation and maintenance costs were greatly increased. In addition to this, the extra burden of dual adjustment was placed upon the operator.

It is an object of this invention to provide a moving picture machine which is adapted to project separate reels substantially continuously.

Another object is to reduce the cost of operating moving picture machines by an association of parts which permits of a single adjustment for a plurality of machines.

Yet another object is to simplify the construction of an apparatus of this character by utilizing a single driving motor for a plurality of projectors.

A further object is to facilitate cinematographic operation by providing a single source of light for a plurality of projectors.

I accomplish these and other important and related objects by providing an elongated frame on which is slidably mounted a plurality of projectors adapted to be moved to produce association with a single source of light and a single lens.

To enable a ready understanding of the invention I have shown in the accompanying drawings a typical device which mechanically embodies its underlying principles. In these the same numerals refer to similar parts throughout several views of which Figure 1 is a front elevation of a machine.

Fig. 2 is a side elevation, part in section, of the device shown in Fig. 1.

Fig. 3 is an enlarged section taken on line 3-3 of Fig. 1.

Fig. 4 is a similar view taken on line 4-4 of Fig. 1.

Fig. 5 is an enlarged detailed view of the trip mechanism.

Fig. 6 is a perspective view of the base of the machine.

Fig. 7 is a top section taken on line 7-7 of Fig. 3.

As shown in Figures 1 and 2, the support for the machine comprises a pedestal 1 of any desired shape. The base of the pedestal (not shown) is firmly secured to any fixed support. Upon the upper portion 2 there is provided a supporting block 3. This is secured to the pedestal by a swivel connection (not shown) adapted to allow circumferential and angular movement of the block with respect to the pedestal. To the upper portion of the supporting block 3 there is secured a frame member designated generally by the numeral 4. These parts may be joined by detachable screw means such as bolts and nuts to facilitate the assembling of the apparatus and to allow access to the adjustment means in the supporting block 3.

The frame 4, as shown more particularly in Figure 6, comprises a bottom plate 5 which is cut out to present the extending parallel supporting arms 6, and the angularly disposed extensions 7 and 8. Spaced above the lateral arms 6 and screwed thereto by the side piece 9, as by screws 9', are the upper supports 10. These extend the full length of the frame and are cut out to present guide channels 11, for a purpose to appear more fully hereinafter. The forward top support 10 is formed with a central plate extension 12. Likewise, the rear upper support 10 is provided with a central laterally projecting arm 13. This arm is cut out centrally to form an elongated slot 14. The extensions 12 and 13 are fastened to the lower frame members 7 and 8 through the intermediacy of the intermediate vertical extension 15 and the end section 16, to insure a rugged supporting structure for the machine.

The arms 12 and 13 are adapted to support the lens and shutter mechanism, and the lamp house respectively. To mount the lamp house there is provided a plate 17 of any convenient length and of a width corresponding to the width of the co-acting extension 100

13. Fixedly secured to the rear end of this extension, through the threaded collars 18, are the vertical upper supporting rods 19. These rods are adapted to receive and support 5 the lamp house in an adjustable position in a manner to be more fully described. The body of the plate is bored, along its central plane, to present a plurality of apertures. In these are received the securing members 10 20 which extend beyond the slot 14 and are threaded at their lower ends to receive the lock nuts 20'. As will be understood, these nuts are of such size as to abut the bottom of the plate 13 adjacent the side of the slot. 15 It will be appreciated that by reason of this structure, plate 17 may be moved longitudinally of the extension 13 to the limit allowed by the slot 14 and locked in any desired position of adjustment. 20 Adapted to be mounted upon the supporting rods 19 is a lamp house generally designated by the reference numeral 68. The lamp house is provided with suitable extensions 74, provided with openings there- 25 through so that they slip over the rods 19. Set screws 75 are threaded into the outer end of the extensions 74 in order that the lamp house may be adjusted vertically if desired and securely held in adjusted position upon 30 the supporting rods 19.

The lamp house 68 may be of any conventional design desired, and is provided with suitable ventilating caps 69, a light source such as the bulb 70, reflector 71 and lenses 72.

35 For the purpose of obtaining entrance to the lamp house it is provided with a suitable closure 73 and a catch for securing the same. As may be noted in Figure 2, upon the lower arm 8 of the frame below the lamp house, 40 there is secured in any conventional manner, a suitable current regulator 115 for controlling the current used by the device.

As will be noted on reference to Fig. 6, a support frame for the lens and shutter mechanism is mounted on the forward part of the support 7. This frame may comprise a single piece of material having the vertical sides 21 and 22 and an intermediate top section 23. The terminal of the side 21 is bent angularly to form a securing flange 24. Through the intermediary of this flange the shutter support may be rigidly attached to the extension 7 by suitable means such as tap screws 25. Similarly, the rear side 22 is 50 flanged at 26 and is fastened to the extension 12 by the screw means 27. It will be noted that the vertical extension 15 is formed with a lateral flange 28 which provides a wide bearing surface to which the extension 55 12 is fastened. It will be understood, of course, that while the front and rear members 21 and 22 and the top member 23 form a single piece of material, this may be made up of several pieces fastened together in any desired manner.

The front plate 21, near its upper end, is apertured and provided with a collar 29 in which, as will be noted, a lens may be mounted. On its interior face this plate is formed with a collar 30 which is adapted to serve as a bearing for a shutter shaft. Similarly the rear plate 22 is formed with an elongated sleeve 31 which is of the same diameter and is aligned with the collar 29. This sleeve receives the tube 32 in which are mounted magnifying lenses, in a well-known manner. Spaced below the sleeve 31 and mounted in the rear plate 22 is a bearing collar 33. This is horizontally aligned with the collar 30 and cooperates with the latter to support the shutter shaft for rotative movement. The rear plate 22 in addition, is tapped, as at 34, to receive a securing means 35 such as screws which rigidly support a projecting apertured brace 36. Below the brace the vertical support 15 is drawn out to provide the integral apertured extension 37. Near its free end this extension is apertured and serves conjointly with the brace 36 to support one of the shafts in the power transmission line of 90 the shutter.

The frame member and its associated parts, hereinbefore described, are adapted to support a motor which operates the shutter and the projector machine. The electric motor, 95 designated on the drawings by the numeral 38, may be of the usual type. This is supported on the central portion 5 of the frame by means of the bed plate 39, in the usual manner. Centrally mounted on the lower section of the frame is a second supporting plate 40. Mounted on this plate by means of screws 41 are two journal boxes 42. These may be of the usual split bearing type.

The motor 38 is provided with a driving shaft 43, which projects toward the center of the supporting frame. To the end of this shaft there is a splined, or otherwise suitably fixed, grooved pulley 44. The bearings 42, mentioned above, support a shaft 45. Intermediate its ends and keyed on this shaft are the friction driving wheels 46, for a purpose to appear presently. As will be seen upon an inspection of Figure 7, the shaft 45 also carries a driven grooved pulley 47. Secured to the pulley, or directly to the shaft 45, is a bevel driving gear 48. The driven shaft 45, is adapted to impart rotatable movement to the shutter. To accomplish this the bushed shaft support 49 is screwed on the supporting plate 40. This may be formed integrally with, or detachably from the plate. A driven shaft 50 is journaled near one of its ends in the bushing support 49 and near its other end in a suitable aperture in the vertical extension 15. At each end there are keyed to the shaft the bevel gears 51 and 52. It will be understood that these gears have an integral collar, which is tapped to receive a set screw for the purpose of affixing them 130

on the shaft. The gear 51 meshes with the corresponding gear 48 and receives motion therefrom. A driving belt 53 fits in the grooves of the pulleys 44 and 47 and transmits motion of the shaft 43 to the shaft 45.

The motor and transmission mechanism, above described, are associated with the shutter mechanism. As appears in Figures 2 and 3 shaft 54 is journaled near its ends in the bearing portions of the supports 36 and 37. Below the support 37 there is affixed to the shaft a bevel gear 55. This gear, like gears 51 and 52, is formed with an integral reduced sleeve or collar 56 which may be bored and the aperture internally threaded to receive a set screw, by means of which the gear is connected to the shaft. To the upper end of the shaft there is affixed in a similar manner a second bevel gear 57. It will be noted that the lower portion of the gear collar 58 rests upon the contiguous portion of the bracket 36 and serves, in conjunction with the collar 56, to prevent vertical displacement of the shaft.

As has been indicated hereinbefore, the front and rear plates 21 and 22 are adapted to support a shutter shaft. This is indicated on the drawings by the numeral 59. At each end the shaft is provided with bearing collars 60 and 61 which nest in corresponding apertures in the bearings 30 and 33 and support the shaft for free rotative movement. Adjacent the collar 61 the shaft carries a bevel gear 62, affixed thereto in the manner already described. This gear meshes with the corresponding bevel gear 57. Intermediate its ends and adjacent the collar 60 there is mounted on the shaft a shutter wheel 63. As shown more particularly in Figure 1, this comprises a rim 64 and the diametric vanes 65. The vanes are joined at the center to an elongated sleeve 66 which is apertured as at 67 for the purpose of affixing the shutter wheel to the shaft.

It will be noted that driving pulley 44 is of the same diameter as the driven pulley 46 and also that the gears 48, 51, 52, 55, 57, and 62, are of the same size. The operation of the shutter mechanism will be appreciated from the foregoing description. When the motor is started, by throwing in a switch (not shown) pulley 44, through the belt 53, operates the pulley 47. Since these are of the same diameter the shaft 45 is driven at the same speed as the shaft 43. Movement of the shaft 45 is transmitted to the shutter wheel 63 through the transmission mechanism including the shafts 50, 54, and 59, and their interconnected gears. The shutter wheel, as will be appreciated, revolves at the same speed as the motor shaft.

The two machines are slidably mounted in the frame 5 for selective operation with respect to the shutter and light source. These machines are identical in construction and

hence but one will be described, it being understood that what is said of one applies to the other. Each machine comprises a housing 76, on the top of which is fixedly mounted a film box 77 which has the usual glass insert

78 for permitting a view of the interior. As

is known, on the interior of the box is mounted a spool from which the film is unwound.

The mechanism for operating the film may be

of any desired type. This is shown con-

ventionally on the drawings as comprising

the sprocket 79 which engages the small gear

80. The gear 80 connects with the lower

sprocket 81 which in turn is directly associ-

ated with the intermediate sprocket 82 and

intermediately through the driving belt 83 to

the film box spindle 84. The intermediate

sprocket 82 carries a fly-wheel 85 and is in

driving connection, through the belt 86, with

the motor driven pulley 87. The film 88 is un-

wound from the upper film box and due to the

inter-action of the driving train, passes over

suitably positioned guide rollers through the

path of light emanating from the lamp house,

to be finally wound on the spool in the lower

film box. The mechanism for moving the

film is adapted to be driven from the same

source of power as operates the shutter mech-

anism. The apparatus for accomplishing this

is shown in Figure 4. As there depicted, a

depending support block 89 is fixed to the bot-

tom of the house 76. Mounted upon one of

the frame members 10 so as to be in the lat-

eral path of each of the machines 76 is a block

90. Integrally formed with or detachably

mounted upon this block is a lug 91 having

oppositely projecting abutment extensions

92. It will be seen that the block 89 is bored

out to present a tubular aperture 93. Into

this aperture is fitted a buffer mechanism.

This comprises essentially a shank 94 formed

at one end with head 95 which is adapted to

slidely engage the sides of the slot 93. To

the other end of the shank 94 is secured an

abutment collar 96. Interposed between the

collar 96 and the adjacent side of the block

89 is a buffer spring 97. It will be seen that

when a force is applied on the abutment collar

96 the spring 97 is compressed and the shank

94 slides longitudinally in the block 89.

The lower section of the block 89 is adapted

to carry the driving means for the film mech-

anism. This member is bored to form a cylind-

rical aperture in which is nested the sleeve

98. To one end of the sleeve a grooved driv-

ing pulley 87 is secured by means of the set

screw 100. The opposite end of the sleeve is

drawn out to provide a shoulder 101 which

fits in a correspondingly shaped depression

in the support block. Fitting in the bore of

the sleeve is a driving shaft 102. This is

operatively connected with the sleeve by a pin

and slot connection 103, in such a manner as to

cause these elements to revolve together while

permitting a limited degree of relative lon-

itudinal movement. At its inner end there is keyed to the shaft 102 a friction wheel 104. This is formed with an integral circular collar 105 through which the wheel may be detachably fixed to the shaft. Encircling the shaft 102 and positioned between the shoulder 101 and collar 105 is a helical buffer spring 106. It will be observed that when one machine is in its idle position (as shown to the right in Figure 4) the plunger 94 is forced outwardly so that the head 95 abuts the closed end of the slot 93. In this position of the several parts, the abutment head 96 projects a considerable distance beyond the wheel 104. Likewise the shaft 102 is forced outwardly, by the force exerted by the spring 106, until the terminal collar 107 abuts the contiguous face of the pulley 87.

As has been described hereinbefore the frame members 10 are cut out to form the channels or grooves 11. In the bottom of each machine 76 are journaled a plurality of anti-friction rollers 108. These fit into the grooves and guide the machine in its traversing movements on the frame. To facilitate the lateral movement of the machines each housing is provided with a hand grip 109.

It is desirable to provide means which serve to hold the machine in the proper position during operations as well as in its idle position. In Figure 5 I have shown a device for accomplishing this. This comprises a latch 110 which is pivoted, as at 111, to a convenient part of each machine 76. This has an angularly disposed toe 112 which is adapted to engage a notch 113 cut out of the frame member 10. Suitably mounted on the machine and bearing directly against the heel of the latch is a leaf spring 114. The parts are so arranged that the toe 112 engages the vertical face of the notch as the machine approaches its position of rest adjacent the end of the frame. A similar notch for each latch is cut out in the frame so as to lock the machine in its operative position, that is to say, near the center portion.

The operation of the device will be apparent from the foregoing description. The lamp house may be properly adjusted and locked in the desired position by manipulation of the adjustment screws 20 and 75. The frame, including the machine, lamp housing, and shutter mechanism may be traversed to cause it to assume the proper position for the projection of a picture. Such movement is permitted, as has been described, by reason of the swivel mounting of the frame on the supporting block 3.

When the motor is energized, rotative movement of the motor shaft is transmitted by the pulley 44 and belt 53 to the driven shaft 45. As has been explained, this drives the shutter wheel at the same rate of speed through the connections including the shafts 50, 54, 59 and their inter-meshing gears. It

will be understood that the gears 46 are positively connected to the shaft 45 and hence rotate with it.

When it is desired to move one machine into operative position the handle 109 may be grasped and the machine pushed towards the center. During this movement the toe of the latch rides on the inclined face of the notch 113. As the machine approaches the operative position the abutment plug 96 abuts the lug extension 92 and effectively retards the movement of the machine. As the machine continues in its lateral movement the buffer spring 97 is compressed and the driven member 104 frictionally engages its corresponding driving wheel 46. During the initial engagement of these members the shaft 102 slides longitudinally in its co-acting sleeve and the spring 106 is compressed. At the same time the shaft 102 drives the film mechanism through the connections, outlined hereinbefore. When the machine has reached its operating position the leaf spring 114 forces the toe of the latch into the center notch. The toe is thereafter firmly retained in that position by reason of the force exerted by the compressed springs 97 and 106. It will be appreciated that when the parts attain this position the single motor 38 drives the shutter mechanism and also causes the film to be unwound and pass through the path of light. The speed at which the film moves can be regulated by adjusting the differential of the pulleys 87 and 82.

It will now be seen that I have provided a moving picture machine which may be operated substantially continuously. When the reel on one machine is completely unwound the latch mechanism may be tripped and the machine moved out of position while the second machine is simultaneously moved into operative position. By utilizing a single motor, shutter mechanism, and lamp house mounted on a single pedestal, the cost of installation, operation and replacement is greatly reduced and the operation itself simplified. The described apparatus is compact and may conveniently be handled by one operator.

While I have shown and described a preferred embodiment of my invention it is to be understood that this is but a typical apparatus which embodies the underlying principles herein set forth and since these may be incorporated in other specific mechanical structures I do not intend to be limited to that shown, except as such limitations are clearly imposed by the appended claims.

I claim:

1. A motion picture machine comprising a base, an elongated frame adjustably mounted on the base, a shutter mechanism supported on the frame, a plurality of projector machines laterally movable on the frame and operating means comprising a motion transmission mechanism positively connected to

the shutter and adapted to be detachably coupled with each projector machine.

2. A motion picture machine comprising a base, an elongated frame adjustably mounted on the base, a shutter mechanism and a lamp house supported on the frame, a plurality of projector machines laterally movable on the frame, and operating means comprising a motion transmission mechanism positively connected to the shutter and adapted to be detachably coupled with each projector machine.

3. A motion picture apparatus comprising a base, a frame having a lamp house, shutter mechanism and a prime mover thereon, a plurality of projector machines slidably mounted on the frame, said prime mover being positively connected to the shutter mechanism and also to a plurality of friction wheels, means on each of said projector machines adapted to engage said friction wheels so that either projector machine may be actuated when it is in operative relation with the lamp house and the shutter mechanism.

4. A motion picture apparatus comprising a base, a frame having a lamp house, shutter mechanism and a prime mover thereon, a plurality of projector machines slidably mounted on the frame, said prime mover being positively connected to the shutter mechanism and also to a plurality of friction wheels, means on each of said projector machines adapted to engage said friction wheels so that either projector machine may be actuated when it is in operative relation with the lamp house and shutter mechanism, and means for securing each projector machine in such position.

5. A motion picture apparatus comprising a base, a frame mounted thereon, a lamp house, shutter mechanism and a prime mover on the frame, a plurality of projector machines slidably mounted on the frame, said prime mover being positively connected to the shutter mechanism so as to drive the same, and also connected to a plurality of friction wheels, a block depending from each of said projector machines, said block carrying a spring pressed shaft, a friction wheel on one end of said shaft, means on the other end of said shaft for actuating the projector machine upon rotation of said shaft, said friction wheel on each projector machine adapted to engage a friction wheel driven by said prime mover when said projector machine is in operative relation with the lamp house and shutter mechanism.

6. A motion picture apparatus comprising a base, a frame mounted thereon, a lamp house, shutter mechanism, and a prime mover on the frame, a plurality of projector machines slidably mounted on the frame, said prime mover being positively connected to the shutter mechanism so as to drive the same and also connected to a plurality of

friction wheels, a block depending from each of said projector machines, said block carrying a spring pressed shaft, a friction wheel on one end of said shaft, means on the other end of said shaft for actuating the projector machine upon the rotation of the shaft, said friction wheel on the projector machine adapted to engage a friction wheel driven by said prime mover when the projector machine is in operative relation with the lamp house and shutter mechanism, and means for securing each projector machine in operative position.

7. A motion picture apparatus comprising a base, a frame thereon, a lamp house, shutter mechanism, and a prime mover positioned upon said frame, a plurality of projector machines slidably mounted on the frame, each of said projector machines being provided with a depending arm having an opening extending therethrough, a sleeve mounted in said opening so as to rotate therein, a shaft positioned within said sleeve so as to rotate therewith, said shaft being slidable longitudinally of said sleeve, means upon one end of said sleeve for connecting the same to the projector machine, a spring upon the other end of said shaft, a friction wheel adjacent said spring, said prime mover being positively connected to the shutter mechanism and to a plurality of friction wheels, the friction wheel associated with each projector machine adapted to engage a friction wheel driven by said prime mover when said projector machine is in operative relation with the lamp house and shutter mechanism, and means for securing the projector machine in such relation.

8. A motion picture machine comprising a base, a frame surmounting the base, a shutter mechanism and a prime mover positioned on said frame, a plurality of projector machines slidably mounted on the frame, said prime mover being positively connected to said shutter mechanism so as to actuate the same, means carried upon each of said projector machines for effecting driving engagement with the prime mover when said projector machine is positioned in operative relation with the shutter mechanism, and resilient means adapted to check the motion of each projector machine as it approaches the prime mover.

9. A motion picture apparatus comprising a base, a frame thereon, a shutter mechanism for a prime mover mounted on said frame, said prime mover being positively connected to said shutter mechanism so as to actuate the same and also connected to a plurality of friction wheels, a plurality of projector machines slidably mounted on said frame, each of said projector machines being provided with spring pressed friction means for effecting a driving engagement between it and the prime mover when said projector machine is in operative relation with the

shutter mechanism, and resilient means adapted to check the motion of each projector machine as it approaches the prime mover.

- 5 10. A motion picture apparatus comprising a base, a frame thereon, a shutter mechanism for a prime mover, mounted on said frame, said prime mover being positively connected to said shutter mechanism so as to
- 10 actuate the same and also connected to a plurality of friction wheels, a plurality of projector machines slidably mounted on said frame, each of said projector machines being provided with spring pressed friction means
- 15 for effecting a driving engagement between it and the prime mover when said projector machine is in operative relation with the shutter mechanism, resilient means adapted to check the motion of each projector machine as it approaches the prime mover, and means for securing each projector machine in operative position.

In testimony whereof I affix my signature.

THEODORE HILL.
